[57] CLAIM

The ornamental design for a drywall screw bit driver, as shown and described.

DESCRIPTION

FIG. 1 is a side elevational view of a drywall screw bit driver in a position after driving a drywall screw, the opposite side elevational view being identical thereto;

FIG. 2 is a bottom view thereof;

FIG. 3 is a top view thereof; and,

FIG. 4 is a side elevational view of a drywall screw bit driver in a telescoped position for receiving a drywall screw prior to driving of the drywall screw, the opposite side elevational view being identical thereto.
